UNITED STATES PATENT OFFICE.

VICTOR NIVOIS, OF BROOKLYN, NEW YORK.

CIGARETTE-CASE.

1,229,502.

Specification of Letters Patent. Patented June 12, 1917.

Application filed April 17, 1916. Serial No. 91,607.

To all whom it may concern:

Be it known that I, VICTOR NIVOIS, a citizen of France, residing at Brooklyn, in the county of Kings and State of New York, 5 have invented new and useful Improvements in Cigarette-Cases, of which the following is a specification.

This invention relates to certain novel and useful improvements in cigarette cases.

10 In the present instance it is my purpose to provide a case which may be used as an original container for the cigarettes, that is to say, the latter are intended to be initially packed in the case at the factory and subsequently vended in such case to the ultimate consumer. Therefore, in the manufacture of my case I prefer to employ relatively cheap or inexpensive material such as tough cardboard, paste-board or the like, but it 15 will of course be understood that if desired the case may be made of more expensive and durable material such as metal, in such instances where it is desired to provide a case which is intended to be frequently re-filled 20 as contra-distinguished from a case which is only intended to constitute an original container for the cigarettes.

Still a further object of the invention is the provision of a cigarette case which is so 30 shaped and constructed as to be easily slipped into the pocket of a coat or other article of wearing apparel, and which will fit therein without causing the pocket to bulge or otherwise present an untidy appearance.

I also propose to provide a case embodying a holder in which the cigarettes may be stowed or packed in such manner as to be constantly maintained in an upright position and also in parallelism, each individual cigarette being held out of contact with the adjacent cigarette or cigarettes, this holder being so mounted relative to the outer cover sections of the case that, when the latter are moved to open position, the holder will assume such an angular position relative to the covers as to enable the cigarette to be conveniently and quickly removed.

Furthermore, I propose to provide a ciga-

rette case wherein the holder, and also the 50 cover portion of the case may each be made from a single blank of material, thus enabling the case to be produced in great quantities at a relatively low cost.

I also propose to provide a case having a 55 holder which is so constructed that when the original contents of the holder have been removed it cannot be readily refilled with other cigarettes without breaking or injuring the latter to such an extent as to render 60 it unprofitable to attempt to refill the case.

With the above recited objects and others of a similar nature in view my invention consists in the construction, combination and arrangement of parts set forth in and falling 65 within the scope of the appended claims.

In the accompanying drawings:

Figure 1 is a perspective view of a form of cigarette case embodying my invention, the case being shown as partially open. 70

Fig. 2 is a transverse vertical sectional view taken through the case of Fig. 1 when the latter is closed.

Fig. 3 is a plan view of a blank from which the holder may be made. 75

Fig. 4 is a top plan view of the holder.

Fig. 5 is a view in side elevation of one wall of a modified form of holder, the connecting web between this wall and the opposite or companion wall of the holder being 80 shown in section.

Fig. 6 is a transverse vertical sectional view taken through a modified form of holder having a wall such as is shown in Fig. 5. 85

In the drawings, the letter A indicates the case cover as an entirety while the letter B designates the holder of the case. The cover A which is preferably made of stiff, tough card-board, paste-board or the like, is preferably manufactured from a single blank suitably cut and shaped to form the two oppositely bowed cover sections 1—1 each of which has a pair of end walls 2—2, the cover sections being connected by a web 3, which constitutes a hinge for the cover sections as will be readily understood. When the two bowed cover sections are closed as shown in

Fig. 2, the longitudinal free edges 4 of these sections converge and meet, due to the taper of the cover sections so that a relatively thin reduced longitudinal edge for the case results, thereby enabling the case to fit snugly and neatly in the pocket and without bulging the latter. If desired, the cover A may have a sheet or covering A' of paper, imitation leather, or other material applied thereon to form an ornamental surface.

The holder B of the case, which is also preferably made of card-board, paste-board or the like, may be made from a single blank, such as is shown in Fig. 3. As will be seen by reference to said figure the blank which is indicated at B' is substantially rectangular in shape but is provided with a projecting tab 5, at one of its shorter side edges, and also has a slot 6 cut therein which extends from one of the longitudinal side edges of the blank inward of the latter to a point beyond the central longitudinal line of the blank. The blank is marked with longitudinal score lines 7-7 and the transverse score lines 8, 9 and 10. In forming the holder the blank is bent on the score lines 8 and 9 to form the end wall 11, is folded on the score lines 10-10' to form the end wall 12 and the lip 13, the latter being pasted against the adjacent side wall 14 of the holder, which extends parallel to its companion wall 15, these side walls being formed by bending the blank as just described. Prior to folding the blank, and preferably in the forming of the blank the section which is to constitute the wall 15 for instance, is slotted to form the integral tongues 16, each tongue being curved and bent inward, as shown in Figs. 1 and 2, when the holder is formed so that the free end sections 17 of each tongue will bear against an adjacent cigarette, and clamping such cigarette against the wall 14, will maintain the cigarette in upright position. As will be seen, the length configuration of the tongues is such that no edge of the tongues extends directly toward the cigarette, the contact being had at a point spaced from the tongue free end, any additional contact increasing the length of contact. Hence, there are no edges presented to bear on the surface of the cigarette in a manner to damage the cigarette or its wrapper even though the tongues are in contact with the cigarettes. Above the row of spaced tongues 16, the wall 15 is separated from the adjacent end walls 11 and 12 of the holder by slitting or cutting as shown at 18, and this upper portion of the wall 15 is intended to be bent outward on the score line 19, thus providing a guide flange by means of which the cigarettes may be readily guided in their insertion and removal from the holder. When the case is closed this flange section of the wall 15 is of

course moved inward until it is parallel with the wall 14, while when the case is open this flange section may be grasped and pressed or pushed outward as shown in Fig. 1.

In order to cover the cigarette clamping tongues 16, and to give a neat appearance to the holder, the latter may be provided with an external covering of paper, fabric or other suitable material, indicated at 20, and which is applied with the adhesive coating 21.

In attaching or applying the holder B to the cover A, the wings 22-22, which are formed by folding the blank along the score line 7, are pasted against the inner faces of the cover sections 1-1, with the elongated box-like portion of the holder resting upon the web 3 which also constitutes a bottom wall for the holder proper.

In Figs. 5 and 6 I have shown a slightly modified form of the invention, in this case the bottom portion of the wall 14^a, which corresponds to the wall 14 of Fig. 1 is provided with a scalloped slit 23, at the ends of which are the vertical slits 24, and which extend both above and below the scalloped slit. The wall is also scored along the line 25, and by bending the wall inward along this line, and by also bending inward the portion 26 of the wall, which lies below the scalloped slit, I provide two oppositely projecting flanges 27 and 28, the edges of which are formed with serrations as will be seen by reference to Fig. 6. When the blank forming this type of holder is cut or formed, the material constituting these flanges will lie in substantially the plane of the wall 14^a. When the blank is folded to form the complete holder these flange sections 27 and 28 will have a tendency to press inward toward the center of the holder and this may be temporarily prevented by holding the flanges pressed outwardly, into substantial parallelism with the wall 14^a, by means of a small piece of card-board, which may be temporarily pressed against the flanges until the holder is filled with the cigarettes, when the card-board piece may be withdrawn and the flanges 27 and 28 permitted to spring inward. Now after the cigarettes have been removed from the holder should it be attempted to re-fill the latter in the ordinary manner the bottom ends of the cigarettes will strike against the flanges, and in all probability be cut, injured or broken by the serrated edges of these flanges, so that after a few attempts, the ordinary purchaser will not attempt to re-fill one of these cases.

While I have herein shown and described one particular embodiment of my invention I wish it to be understood that I do not confine myself to all the precise details of construction herein set forth by way of illustration, as modification and variation may

be made without departing from the spirit of the invention or exceeding the scope of the appended claims.

What I claim is—

5. 1. A cigarette case comprising a pair of cover sections and a holder adapted to be inclosed thereby, said holder comprising a box-like body portion formed from a single blank of material and having a series of cigarette engaging members extending inward from one wall thereof and adapted to contact the cigarettes adjacent the cigarette inner ends, said members having a length configuration to provide contact with a cigarette at a point spaced from the member free end.
10. 2. A cigarette case comprising a pair of hinged cover sections, and a holder adapted to be inclosed thereby, said holder including a box-like body portion and a pair of outwardly extending attaching means all formed from a single blank, said attaching means having a width greater than the width of the adjacent body portion wall and being adapted to lie in contact with and to be secured to the adjacent walls of the cover sections, whereby said attaching means will project above the body portion when the case is closed.
15. 3. A cigarette case comprising a pair of hinged cover sections formed from a single blank, said cover sections having converging longitudinally extending meeting edges, and a holder adapted to be inclosed by the cover sections, said holder comprising a box-like body portion having outwardly extending wings formed at its lower longitudinal edges, said wings having a width greater than the width of the adjacent body portion wall and being adapted to be attached to the inner faces of the cover sections.
20. 4. A cigarette case comprising a pair of hinged cover sections, and a holder adapted to be inclosed thereby, said holder including a body portion having one of the walls thereof separated from and movable relative to the adjacent end walls of the holder at its upper portion, said wall also having a series of inwardly extending cigarette engaging members formed integral therewith and adapted to contact the cigarettes adjacent the cigarette inner ends.
25. 5. In a cigarette case, a box-like holder adapted to receive the cigarettes and formed from a single blank, said holder having one of the walls thereof cut to provide a series of cigarette engaging tongues, said tongues being bent inwardly of the holder and positioned to contact the cigarettes adjacent their inner ends, said tongues having a length configuration to provide contact with a cigarette at a point spaced from the tongue free end.
30. 6. In a cigarette case, a box-like holder adapted to receive the cigarettes and formed from a single blank, said holder having one of the walls thereof provided with a member having means normally extending inward of the holder to constitute barriers for preventing the re-filling of the holders.
35. 7. In a cigarette case, a holder having two substantially parallel side walls, one of said walls having a series of inwardly extending cigarette clamping members, the other of said walls being provided with means for preventing the re-filling of the holder.
40. 8. In a cigarette case, a holder having one wall thereof cut to provide an inwardly extending serrated flange adapted to prevent the re-filling of the holder.
45. 9. A cigarette case comprising a pair of cover sections, and a holder adapted to be inclosed within the cover sections, said holder having a wall thereof formed with a row of inwardly projecting cigarette engaging members, each member being adapted to contact a cigarette adjacent the inner cigarette end to clamp the cigarette against the opposite wall of the holder, said members having a length configuration to provide contact with a cigarette at a point spaced from the member free end.
50. 10. A cigarette case comprising a pair of cover sections, and a non-metallic holder adapted to be inclosed within the cover sections, said holder having a wall thereof formed with a row of inwardly projecting cigarette engaging members, each member being adapted to clamp an adjacent cigarette against the opposite wall of the holder, and a cover sheet applied to the outside of the holder and overlying the cigarette engaging members.
55. 11. A cigarette case comprising a pair of cover sections, and a holder adapted to be inclosed within the cover sections, said holder having a pair of substantially parallel walls, one of which has a row of spaced inwardly bent cigarette engaging tongues formed integral therewith, said tongues projecting in directions away from the open mouth of the holder and having a length configuration to provide contact with a cigarette at a point spaced from the tongue free end.
60. 12. In a cigarette case, a pair of covers, and a holder adapted to be inclosed thereby, said holder having one of the walls thereof provided with a row of inwardly projecting cigarette engaging tongues, the upper portion of the wall being movable relative to the tongue carrying section thereof.
65. 13. A cigarette case comprising a pair of hinged cover sections, and a holder adapted to be inclosed thereby, said holder including a body portion having one of the walls thereof separated from and movable relative to

the adjacent end walls of the holder at its upper portion, said movable wall being adapted to serve as a guide flange by means of which the cigarettes may be guided during insertion and removal from the holder.

14. A cigarette case comprising a pair of hinged covers which are dished or bowed to provide when closed a relatively narrow tapered edge portion, and a holder adapted 10 to be inclosed within the covers, said holder being formed from a single blank cut and

folded to provide a box-like body portion having parallel side walls, the hinge section of the cover constituting the bottom of the holder.

15

In testimony whereof I have hereunto set my hand in the presence of two subscribing witnesses.
